C. L. GOODRUM,
TELEPHONE EXCHANGE SYSTEM,
APPLICATION FILED SEPT. 11, 1916.

Patented Apr. 3, 1917.

UNITED STATES PATENT OFFICE.

CHARLES L. GOODRUM, OF BROOKLYN, NEW YORK, ASSIGNEE TO WESTERN ELECTRIC COMPANY, INCORPORATED, OF NEW YORK, N. Y., A CORPORATION OF NEW YORK.

TELEPHONE-EXCHANGE SYSTEM.

1,221,168.

Specification of Letters Patent. Patented Apr. 3, 1917.

Application filed September 11, 1916. Serial No. 119,510.

To all whom it may concern:

Be it known that I, CHARLES L. GOODRUM, a citizen of the United States, residing at Brooklyn, in the county of Kings and State 5 of New York, have invented certain new and useful Improvements in Telephone-Exchange Systems, of which the following is a full, clear, concise, and exact description.

This invention relates to telephone exchange systems employing machine switching.

Its object is to provide a circuit arrangement for systems of this character wherein a selector, failing to find an idle trunk, will 10 be automatically restored to the beginning of the selected trunk group and again driven over such trunk group, this operation continuing until an idle trunk is found.

To accomplish this result the selector, in 15 the present embodiment of the invention, is provided with a release magnet in addition to the regular release magnet which withdraws both holding pawls. This additional release magnet will withdraw the secondary 20 pawl only, whereupon the brush shaft is restored in so far as its secondary movement is concerned, being retained in its set primary position in operative relation to the selected trunk group by the primary holding pawl. The secondary motor magnet 25 then is operated to drive the selector brushes over such trunk group again.

The invention will be more readily understood when described with reference to the 30 accompanying drawing, which shows only so much of a telephone exchange system as is necessary to a comprehension of the invention.

The invention will be best understood 35 from a detailed description of the operation.

Upon the removal of the receiver at substation A, a line-finder F, the brushes b, b', and terminals t, t', only of which are shown, is set in motion to find the calling line. 40 When the calling line has been extended to a first selector FS, the stepping relay 1 thereof is energized over the following circuit: free pole of battery, right winding of relay 1, arm 2 of the first selector side switch 45 and its first contact, conductor 3, brush b, multiple t, line conductor 4, through the telephonic apparatus at substation A, line conductor 5, multiple t', brush b', conductor 6, side-switch arm 7 and its first contact, left 50 winding of relay 1, to ground. Relay 1 in

attracting its armature, energizes a slow relay 8, which in attracting its armature interposes a break in the circuits of release magnet RM and prepares a circuit for a slow relay 9, which controls the escapement magnet 60 10 and also connects the primary magnet PM to the back contact of the stepping relay 1.

The calling party now operates his sender S to transmit the first digit of the wanted 65 number. The sender S is of the well-known type, which in returning to normal interrupts the line circuit a number of times corresponding to the digit in question. Upon each retraction of the armature of relay 1 70 an impulse is transmitted over the following path to primary magnet PM: ground, armature and back contact of relay 1, armature and front contact of relay 8, which being slow holds its armature attracted though its 75 circuit is interrupted, conductors 13 and 14, secondary off-normal contact SON, magnet PM, free pole of battery. The slow relay 9 is energized in parallel with magnet PM, and remains energized during the transmission 80 of the impulses. This relay in attracting its armature energizes escape magnet 10. The armature of magnet PM is provided with a stepping pawl 37, which engages a rotary ratchet 23 on the brush shaft 21, and rotates 85 the shaft to position a set of brushes 11 in operative relation to the desired trunk group.

When the sender S restores and maintains 90 the line circuit closed, slow relay 9 after a slight interval becomes deenergized, opening the circuit of escape magnet 10, which thereupon passes the side switch to position 2.

In position 2 the following circuit is closed 95 for the secondary magnet SM to drive the positioned set of brushes over the selected trunk group: free pole of battery, contact 15 of release magnet R'M', magnet SM and its armature and back contact, conductor 16, side-switch arm 17 and its second contact, to ground at the armature and front contact of relay 1. The armature of magnet SM is provided with a stepping pawl 34, which engages a vertical ratchet 22 to elevate the 100 shaft 21. In position 2 of the side switch, arm 18 connects the escape magnet 10 in circuit with the test brush of the set of positioned brushes. Idle trunks are those whose 105 test terminals are grounded. The escape 110

magnet is constructed to release the side switch from position 2 to position 3 upon its energization, when the first idle trunk is reached. Therefore, when the first idle 5 trunk is reached, the escape magnet 10 becomes energized over the following circuit: free pole of battery, magnet 10, side-switch arm 18 and its second contact, conductor 19, the test brush of the positioned set of 10 brushes, and the grounded test terminal of the idle trunk. In moving out of position 2, side-switch arms 2 and 7 disconnect the stepping relay 1 from the connecting circuit conductors 3 and 6, and extend the calling 15 line through to the talking brushes of the selector. In this position, side-switch arm 20 connects the release magnet RM to the third or release wire to prepare the release circuit which is closed upon the disestablishment of the connection. The vertical ratchet 22 is normally engaged by a holding pawl 24 and the rotary ratchet by a holding pawl 25. The pawl 24 is integral with the armature 26 of the release magnet R'M', 20 which armature is pivoted on a pin 27. The pawl 25 is integral with the armature 28 of the release magnet RM, which armature is 25 also pivoted upon pin 27.

Upon the replacement of the receivers, a 30 ground is placed upon test wire 19 leading from the connector, and closes the circuit of release magnet RM, this circuit including a primary off-normal contact PON closed upon the first rotary step of the shaft 35 21. This magnet in attracting its armature 28, withdraws the rotary pawl 25, and the arm 29 of such armature acts through arm 30 on the armature 26 to withdraw the vertical pawl 24. The release magnet when 40 energized, locks itself over contact 31 and remains locked up until the brush shaft 21 restores and opens off-normal contact PON. If, however, during the hunting operation of the selector its movement is not 45 stopped, the secondary magnet SM drives the brushes over the entire group, and after the brushes have cleared the last set of trunk terminals, an insulated projection 32 on the brush shaft 21 closes a contact 33 50 and energizes release magnet R'M'. This magnet in attracting its armature 26, withdraws the vertical pawl 24 from the vertical ratchet 22 but does not disturb the rotary pawl 25. The armature 26 in its attractive 55 movement opens contact 15 and closes contact 33'. The opening of the former contact prevents further operation of the secondary magnet SM, and the closing of the latter contact maintains the magnet R'M' locked 60 over a circuit including a contact 35, which closes upon the first upward step of the brush shaft 21. The withdrawal of pawl 24 causes the shaft 21 to drop and when it reaches its lowermost position, the projection 32 opens contact 35, unlocking magnet 65

R'M' which, in retracting its armature, closes contact 15. The closure of the latter contact again causes the magnet SM to drive the shaft 21 upwardly. The operations just described occur until one of the trunks becomes idle, or until the calling party replaces his receiver, releasing the selector. The release circuit for the selector in this case is as follows: free pole of battery, release magnet RM, contact PON, arm 20 and 70 its second contact, armatures and back contacts of relays 8 and 1 to ground. 75

What is claimed is:

1. In a telephone exchange system, in combination with telephone lines, a selector, 80 means for associating calling lines with said selector, trunk groups terminating in said selector, primary and secondary driving magnets for said selector, means for operating said primary magnet to set said selector in operative relation to a trunk group, automatic means for thereupon operating said secondary magnet to drive the selector over said group, means for stopping the selector on the first idle trunk, and 85 means operated if no idle trunk is present for restoring said selector in operative relation to said trunk group and for again driving the same thereover.

2. In a telephone exchange system, in combination with telephone lines, a selector, 90 a brush shaft therefor, means for associating a calling line with said selector, primary and secondary stepping magnets for said selector, primary and secondary holding pawls for said brush shaft, a release magnet adapted to withdraw both pawls, an auxiliary release magnet adapted to withdraw only the secondary pawl, trunk groups terminating in said selector, a sender 100 for operating said primary magnet to set said selector in operative relation to a trunk group, automatic means for thereupon operating said secondary magnet to drive the selector thereover, means operative on the 105 disestablishment of the connection to operate said release magnet to restore the brush shaft, means operated if the selector fails to find an idle trunk for operating said auxiliary magnet to withdraw the secondary 110 pawl, and means for thereupon again operating the secondary magnet to drive the selector over the selected trunk group.

3. In a telephone exchange system, the combination with telephone lines, a selector, 120 trunk groups terminating therein, primary and secondary stepping magnets for said selector, a driving circuit for said secondary magnet, primary and secondary holding pawls for said selector, a release 125 magnet adapted to withdraw both pawls and an auxiliary release magnet adapted to withdraw only the secondary pawl, a sender for operating said primary magnet to set the selector in operative relation to a desired 130

trunk group, means for thereupon closing said driving circuit to step the selector thereover, a testing magnet adapted to be operated upon the finding of the first idle trunk to open the circuit of said secondary magnet, means actuated when the selector reaches the end of the trunk group for operating the auxiliary release magnet, a locking circuit therefor, said magnet being adapted to withdraw the secondary pawl, to open the circuit of the secondary magnet and to close said locking circuit, and means for reclosing said driving circuit and for opening said locking circuit when the selector is restored to operative relation to the 15 said trunk group to drive the brushes again over said group.

In witness whereof, I hereunto subscribe my name this 8th day of September A. D., 1916.

CHARLES L. GOODRUM.
